CLAIM

The ornamental design for a yoga mat, as shown and described.

DESCRIPTION

FIG. 1 is a front-top perspective view of a yoga mat showing my new design;

FIG. 2 is a front-bottom perspective view thereof;

FIG. 3 is a rear-bottom perspective view thereof;

FIG. 4 is a left elevational view thereof where the right elevational view is mirrored thereto;

FIG. 5 is a top plan view thereof where the bottom plan view is mirrored thereto;

FIG. 6 is a front elevational view thereof; and,

FIG. 7 is a rear elevational view thereof.

The broken lines depict portions of the yoga mat that form no part of the claimed design.
